(57) **CLAIM**

The ornamental design for a tray, as shown and described.

DESCRIPTION

FIG. 1 is a front, left perspective view of a tray showing a first embodiment our new design.

FIG. 2 is a front elevational view thereof.

FIG. 3 is a left side elevational view thereof.

FIG. 4 is a top plan view thereof.

FIG. 5 is a bottom plan view thereof.

FIG. 6 is a front, left perspective view of a tray showing a second embodiment our new design.

FIG. 7 is a front elevational view thereof.

FIG. 8 is a left side elevational view thereof.

FIG. 9 is a top plan view thereof; and,

FIG. 10 is a bottom plan view thereof.

The broken line showing of portions of the side walls of the tray and the bottom of the tray is for environmental purposes only and forms no part of the claimed design.

1 Claim, 6 Drawing Sheets
